assignors to Jenn-Air Corporation, Indianapolis, Ind.,
a corporation of Indiana

Filed Sept. 28, 1967, Ser. No. 8,777

Term of patent 14 years

(Cl. D23—155)

FIGURE 1 is a perspective of the front of a fan enclosure embodying the new design;

FIG. 2 is an enlarged fragmentary front elevation showing one corner of the enclosure of FIG. 1;

FIG. 3 is an enlarged fragmentary section taken approximately along the line 3-3 in FIG. 1;

FIG. 4 is an enlarged fragmentary section taken approximately along the line 4-4 of FIG. 1; and

FIG. 5 is a view similar to FIG. 2 showing one corner embodying a modification of FIG. 1, it being understood that the modified enclosure is identical to FIG. 1 except for the corners.

The dominant features of our new design reside in the portions shown in full lines.

We claim:

The ornamental design for a fan orifice enclosure, substantially as shown and described.
